UNITED STATES PATENT OFFICE.

GEORGE J. KELLER, OF OSCEOLA, NEBRASKA.

ALARM-LOCK.

SPECIFICATION forming part of Letters Patent No. 424,886, dated April 1, 1890.

Application filed December 30, 1889. Serial No. 335,340. (No model.)

To all whom it may concern:

Be it known that I, GEORGE J. KELLER, of Osceola, in the county of Polk and State of Nebraska, have invented certain new and useful Improvements in Combination-Locks for Sliding Doors; and I do hereby declare the following to be a full, clear, and exact description of the invention, such as will enable others skilled in the art to which it pertains to make and use it, reference being had to the accompanying drawings, which form part of this specification.

My invention relates to an improvement in combination-locks for sliding doors; and it consists in the combination of a sliding door, and the plate which is secured to the door-frame, with a series of pivoted latches, endwise-moving operating-rods to which the knobs are secured at one end, springs applied to the rods, a bent rod for each latch and which is operated by the movement of the knob, and an alarm, as will be more fully described hereinafter.

The object of my invention is to provide a combination-lock for sliding doors, and which is so constructed that only the person knowing the combination can open the door without sounding an alarm.

Figure 1 is a horizontal section taking through the door just above the lock. Fig. 2 is a view of the operating parts of the lock alone, the knob being removed. Fig. 3 is an edge view of the lock, partly in section. Figs. 4 and 5 are detail views.

A represents a sliding door, which is provided with a handle B, of any suitable description, for moving the door back and forth from the outside, and which handle has a shield C connected thereto for the purpose of hiding from view the ends of the operating-rods D, so that a person cannot see what ones are operated in order to open the door. Placed upon each one of these rods D, to which the handles E are applied at their inner ends, is a spiral spring F, which bears against a latch G at one end for forcing it into an operating position, and against a plate H, which is secured to one side of the door, and which has a series of openings or perforations through it corresponding to the number of endwise-moving operating-rods D. There are any desired number of the latches G', which

are pivoted at their inner ends upon the vertical rod I, which passes down through suitable ears J, secured to or formed upon the lock-plate K, secured to the inner side of the door. Each one of the latches G is provided with two shoulders or catches upon its outer end, so as to engage with either one of the edges of a corresponding opening which is made through the plate L, which is secured to the door-frame, as shown in Fig. 1. These latches pass through the perforated plate M, which is secured to the edge of the door, and which plate limits their lateral movement at their outer ends.

Fastened to the inner end of each of the endwise operating-rods D is a knob or a handle E, by means of a screw O, the ends of the rods D being each provided with two screw-holes P, as shown, so that the handle E can be adjusted into either one of two positions, according as the corresponding latch G is moved into or out of the combination. The inner end of each knob or handle E that is in the combination is made to bear against its corresponding latch G, as shown in Fig. 1, so that when a rod D is pulled from one end or pushed from the other the tension of its spring F is overcome and the latch G moved far enough to allow the end of the latch to be disengaged from the outer edge of the opening made in the plate L, and the door pushed open.

The latch shown in Fig. 1 is in the combination, and is limited in its movement toward the door, as hereinafter described, for the purpose of preventing the inner shoulder of the said latch from engaging the inner edge of the opening made in the plate L.

Formed upon the inner end of each of the knobs or the handles E is a projection Q, and these projections are turned so as to project downward from the inner end of the hollow knob or handle when it is used in the combination, and when any number of the latches are thrown out of the combination the screw O is removed from the knob or handle E, and the knob reversed in position, so that the projections Q extend upward, as shown in Figs. 2 and 3. Used in connection with these knobs or handles E are the partially-revolving rods R, which are provided with cranks S at their inner ends and have their outer ends turned downward and provided with the knobs T, so

as to strike against a metallic plate U and thus sound an alarm when the endwise-moving rods D, which are not in the combination, are used. These rods R are supported in suitable bearings V, and are prevented from having an endwise movement by means of enlargements W on each rod, and which enlargements catch upon opposite sides of one of the bearings V. These bearings V consist of vertical rods or castings, as shown in Fig. 5, and which are made in two parts, so as to allow the outer part to be removed at any time, and the rods R placed in or moved from position at the wish of the operator. The cranks S on the inner ends of the rods R catch behind the projections Q on the inner ends of the knobs or handles E, and when any one or more of the rods D, which are not in the combination, are moved, these cranks are operated so as to cause an alarm to be sounded, and thus give notice of an intruder. When certain of the latches are to be used in the combination, the corresponding knobs are removed from the rods D and turned around, so that the projections Q extend downward, and thus do not operate the cranks S of the rods R. Those latches which are not to be used in the combination have their corresponding knobs attached to the rods D in such a manner that the projections Q extend upward, so as to cause the rods R to partially revolve when the knobs and rods are moved endwise.

In order to limit the lateral movement of each latch G, whether in or out of the operative combination, an L-shaped casting N is used, and which is secured inside of the openings in the plate M, as shown in Fig. 3, by suitable fastening-screws. When these castings N are turned in one position, they limit the distance that the latches shall be moved inward by the pressure of the knobs or handles, and when placed in another position they limit the distance that the latches shall move outward.

As shown in Fig. 3, the two upper latches are in the combination, while the three lower ones are shown out of the combination. The latches which are in the combination are allowed to move outward and engage the outer edge of the openings made in the plate L, but are prevented from moving inward, so as to engage the inner edge of said openings by placing the castings N between the said latches and the inner edge of the openings; but the latches which are out of the combination are prevented from moving outward, so as to engage the outer edge of the said openings in the plate L by placing the castings N between them and the outer edge of the opening, while they are allowed to move freely inward and engage the inner edge of the openings when their respective rods D are operated.

When the castings N are placed inside of the latches G and the corresponding rods D are moved endwise, the latches are prevented

from being moved inward past the middle position, where the door can be freely opened. All of the latches in the combination freely engage with the outer edges of the openings made in the plate L when the door is closed, while those latches not in the combination do not engage with it at all. If the latches in the combination are moved, they unlock the door; but if the latches not in the combination are moved they lock the door instead of unlocking it.

For the purpose of regulating the distance that the rods D are to be moved when they are in or out of the combination the two holes P in the rods D are used. The knobs or handles E, corresponding to the latches G, which are in the combination, are moved inward as far as possible upon the ends of the endwise-moving rods D, and the screw O is passed through the inner screw-hole P and the knobs of those latches which are not in the combination are moved outward upon the ends of the rods D, and the screw O is passed through the outer screw-hole, so that they will have a longer movement than those which are in the combination, and thus cause a loud alarm to be sounded; but a very slight movement of the endwise-moving rod D of any of the latches which are out of the combination is necessary to cause the latch to engage with the plate L so as to lock the door.

The different combinations are made as follows: If any latch or latches are wanted in a combination at the pleasure of the owner the screw O, as shown in Fig. 1, is moved from the knob of every latch that is wanted in the combination and the knob is removed from the end of the rod D and then turned half way around, so as to bring the projections Q on its lower side, where it will not operate the crank S on a rod R. The corresponding castings N to all of the latches needed in the combination are secured in position, so that they will be placed inside of the latches, as shown in the upper portion of Fig. 3. All of those latches which are not wanted in the combination have their knobs or handles E secured to the corresponding endwise-moving rods D, so that the projections Q extend upward and catch in front of the cranks S, and the knobs or handles have the screw O passed through the outer hole P in the rod D. The object in having two holes P is to give a longer movement to the endwise-moving rods D when the knobs are moved outward than they would have when the knobs are moved inward and the screw is passed through the inner hole. When the knob is forced inward and the screw passed through the inner hole, the inner end of the knob is brought much nearer to the latch G, and the rod consequently has a shorter movement.

I do not limit myself to any particular number of knobs or latches, for this may be varied at will. Of the number used any one, two, or more of the latches may be used in the combination or not, as may be preferred. These

latches are kept separate from each other at their inner ends upon the rod I by means of tubes or collars, which are placed upon the rod I for this purpose. Any suitable sounding metal may be used in making the plate U, which is attached to the plate K by means of supports X.

Having thus described my invention, I claim—

- 10 1. The combination of the pivoted latches provided with double catches at their outer ends, and perforated plate L, secured to the door-frame and with which the ends of the latches engage, the endwise-moving spring-actuated rods D, which pass through the door, and the latches, the knobs or handles secured thereto and provided with projections, the

crank-rods, and the plate U, substantially as shown.

2. The combination of the latches G, pivoted at their inner ends and provided with double catches at their outer ones, the perforated plate L, secured to the door, the plate M, secured to the door, the castings N for limiting the movement of the latches, and the 25 spring-actuated endwise-moving rods D, substantially as described.

In testimony whereof I affix my signature in presence of two witnesses.

GEORGE J. KELLER.
